UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,359,565.

Specification of Letters Patent. Patented Nov. 23, 1920.

Application filed October 11, 1917. Serial No. 195,916.

To all whom it may concern:

Be it known that I, JOHN H. BELL, a citizen of the United States, residing at South Orange, in the county of Essex and State 5 of New Jersey, have invented certain new and useful Improvements in Telegraph Systems, of which the following is a full, clear, concise, and exact description.

This invention relates to telegraph systems, and more particularly to improvements in telegraph transmitting systems for use with circuits having low time constant characteristics, such as submarine cable circuits.

15 The principal object of this invention is to provide improved apparatus and systems to overcome the phenomena of electrical distortion inherent in submarine cable telegraphy.

20 In submarine cable telegraphy it is a well-established fact that the speed of working and the quality of definition or distinctiveness of received signals is dependent on the extent to which a cable may be maintained 25 free from excess charge of either polarity during brief time intervals, or at a true zero current condition with respect to the polarities of impulses of current employed in transmission.

30 When the signal combinations consist of unbroken reversals of current in which certain half-waves are incremented, it is true that when two incremented half-waves of the same polarity are separated by a half-wave 35 of normal amplitude, the second incremented half-wave will produce a signal, say, on a siphon recorder tape, having an amplitude greater than should be attained by such incremented impulse. This is, of course,

40 due to the fact that a portion of the first incremented impulse charge is retained by the cable and not overcome or properly reduced by the intervening inverse impulse of less strength and accordingly such charge 45 augments the second incremented impulse, thereby distorting the zero condition of the cable.

The present invention contemplates the 50 application of curbing effects to the regular signaling impulses in a manner to render each current impulse effective as a message transmitting impulse. The corrective scope of the present invention and the gain in transmission speed effected are such that im- 55 pulse receiving means sufficiently effective

for the control of a receiving printer may be reliably and efficiently operated, thereby extending the field of printing telegraphs to commercial cable operation.

To the above end, there is provided, in 60 connection with a source of periodic alternating currents, preferably of sine wave form, the usual transmitting contacts, a plurality of electroresponsive switching devices and distributor means to selectively control 65 the strength of current impulses impressed on a cable circuit for message transmission. In connection with the message transmission equipment, other electroresponsive switching devices are automatically controlled 70 thereby in a manner to further modify the strength of certain message impulses in a manner to prevent an asymmetrical zero polarity effect in a cable, as already pointed out. 75

This invention is illustrated diagrammatically in the accompanying drawing, in which only so much of a telegraphic equipment is shown as will be necessary to a clear understanding of the system. 80

In the drawing Figure 1 illustrates a transmitting equipment suitable for practising the features of this invention; Fig. 2 illustrates the wave form of alternating currents with curves to indicate modifications 85 thereof effected through the present system; and Fig. 3 illustrates an alternate arrangement of the transmitting equipment which may be substituted for the equipment shown in Fig. 1. 90

Referring to the drawing, Fig. 1, a cable indicated by the reference character 13, is connected through a winding 15 of a transformer 14 to an earth connection 17. A second winding 16 of the transformer is 95 included in a closed loop formed through a resistance unit 19 and a single phase alternating current generator 18. A grounded source of current 33 is connected by way of a bus conductor 34 with five transmitting 100 contacts collectively indicated as a group A, and preferably arranged to be controlled by means of a punched tape as well understood in the art.

For convenience in illustrating, the present invention is herein shown as applied to a transmitting system wherein each character, symbol or other operation transmitted, is distinguished from all other characters, symbols or operations through a particular 110

permutation of five impulses of current of normal or incremented strength. A magnet 53 connected to the current bus 34 is controlled through segments 55 and 56 of a distributor E for operating suitable mechanism (not shown) to step or advance a punched tape which may be assumed as present for controlling the operation of the contacts A, as already mentioned. A group of five 10 relays B controlled by the contacts A prepare circuits to five segments of the distributor E and also control the operation of five relays comprising a group C. The relays C control the inclusion or exclusion of 15 resistance units comprising a group D in respective circuits prepared to the segments of the distributor E by the relays B.

The distributor E may be of any suitable form and assuming it to be of a rotary type 20 the contactor brushes 38 and 39 thereof would be carried clockwise by a radical arm rotated in synchronism with the generator 18. The synchronous relation is to be such that the zero current potential moments between the alternations of a current cycle occur at such times as the brush 38 is leaving one segment and passing to a next segment. It is also provided that following the transmission of five successive character selecting 25 impulses the brush 39 will engage the segments 55 and 56 to operate the tape control magnet 53 during a zero-potential instant of the generator 18. It will be obvious that the synchronous relation described may result in 30 maintaining a fixed polarity relation between the generator and the transmitter contacts A and in turn with the five transmitting segments of the distributor. For the purpose of simplifying the description, a polarity relation 35 has been assumed and the contacts A and the segments of the distributor correspondingly marked with the conventional polarity signs.

By way of a first illustration let it be assumed that a non-perforated portion of the control tape is present at the contacts A and that all of the contacts remain open during a five impulse interval. In this case the relays B and C thereby remain unoperated and five 40 impulses of current developed by the generator 18 will only circulate in the loop circuit formed through the resistance unit 19, and the transformer winding 16. In phase with the assumed polarity arrangement, as 45 marked at the contacts A, the five impulses would progress as positive, negative, positive, negative and positive, and, due to the presence of the resistance unit 19, each impulse would be of predetermined minimum 50 strength. As translated to the winding 15 of the transformer five corresponding impulses would traverse the cable 13 in the form of symmetrical alternating currents, and, assuming that the speed of the generator 18 is 55 such that the current frequency is at a proper

ratio to the time constant of the cable, such currents will maintain a uniform electrical condition or true zero therein, the wave form of the currents being indicated at F in Fig. 2 of the drawing. During such five-impulse 70 interval the brushes 38 and 39 will move as usual and following the fifth impulse the brush 39 will pass over the segments 55 and 56, thereby completing a circuit through a conductor 54 and the tape control magnet 53 75 to the current source 33, thereby advancing the tape to establish a next combination of five impulses at the contacts A.

For the purpose of a second illustration, let it now be assumed that perforations at the 80 present position of the transmitter tape result in closing each one of the contacts A. In this position current from the source 33 through the bus conductor 34 traverses contacts 1, 21, 41, 61 and 81 to respectively operate the relays 2, 22, 42, 62 and 82. Separation of contacts 4, 24, 44, 64 and 84 of these relays respectively disconnect the relays 26, 46, 66, 86 and 6. The normal contacts 7, 27, 47, 67 and 87 of the relays C accordingly remain closed, thereby including a bus conductor 35, extending in derived circuit from the closed circuit loop of the generator 18, by way of respective contacts 3, 23, 43, 63 and 83 of the relays in the group A to respective 90 segments 10, 30, 50, 70 and 90 of the distributor E. A conductor 36, connected in derived circuit at a point on the generator loop opposite to the connective point of the conductor 35 with respect to the resistance 100 unit 19, is connected to a collector ring 37 of the distributor. It will, therefore, be clear that in phase with the generation of each one of the five impulses corresponding with the present combination, the brush 38 of the 105 distributor will be over a corresponding segment, thereby establishing a short circuit on the resistance unit 19. For the first impulse, this shunt circuit may be traced over the bus conductor 35, contacts 3 of the relay 2, the 110 contacts 7 of relay 6, segment 10, brush 38, collector ring 37, thence by way of the conductor 36 to the opposite side of the resistance unit 19. It will be clear that for each of the remaining four impulses the resistance 115 19 will, in turn, be short-circuited through similar paths extending through circuits controlled by respective ones of the relays B and C and the distributor E. Since each one of the five impulses just described will be of 120 uniform incremented strength their translation through the transformer 14 into the cable 13 will produce therein symmetrical or true zero potential between the alternations or one-half cycles, corresponding with the 125 wave form shown at G in Fig. 2 of the drawing.

In order to make a third illustration, let it now be assumed that following the last one of the five impulses just described, the brush 130

39, in passing over the segments 55 and 56, operates the magnet 53 to advance the transmitter tape to a new combination of perforations, whereby at the group A contacts 5 1, 41 and 81 will be closed while contacts 21 and 61 will remain open. In the group B relays 2, 42 and 82 will be operated while the relays 22 and 62 will remain inert. Such condition of the relays B effects at the 10 group C, operation of relays 46 and 86 while relays 6, 26 and 66 remain inert. The operating circuit for the relay 46 may be traced from the left-hand side of a current source 31, a conductor 32, the contacts 5 of the relay 15 2, the contacts 24 of the relay 22, a conductor 52, thence through the winding of the relay 46 to the opposite side of the source 31. For the relay 86, the circuit extends from the left-hand side of a current source 71, a conductor 72, contacts 45 of the relay 42, contacts 64 of the relay 62, a conductor 92, thence through the winding of the relay 86 to the opposite side of the source 71. 20

The transmitting apparatus being retained 25 in the position described, the first one of the five impulses will be of positive polarity and, due to the brush 38 being at a corresponding moment over the segment 10, a short circuit around the resistance unit 19 30 will be thereby established as already described, therefore, this impulse will be incremented to a maximum strength. The next impulse will be of negative polarity, but, due to the relay 22 being inert, the circuit from the segment 30 stands open at the contacts 23 of this relay. Therefore the resistance unit 19 effects a predetermined minimum strength for this negative impulse. For the third impulse, which is of positive 35 polarity, a circuit may be traced by way of the bus conductor 35, the contacts 43 of the relay 42, contacts 48 of the relay 46, a resistance unit 49, segment 50 of the distributor, the brush 38, now at this segment, the 40 collector ring 37 and conductor 36. It will be clear that the resistance unit 49 becomes effective through this circuit to form a parallel path around the resistance unit 19, thereby reducing or curbing this impulse 45 below a maximum value, which would otherwise be present in carrying out the assumed code unit under consideration. For the fourth impulse the resistance unit 19 is effective to reduce this negative impulse to a 50 minimum current strength. The fifth impulse of positive polarity instead of attaining a maximum incremented value, due to the operated position of the relay 82, will be curbed through the presence of a resistance 55 unit 89 included through the contacts 88 of the relay 86 in the shunting path formed over the segment 90 of the distributor in a manner similar to that described for the third impulse. 60

65 Referring to portion H of Fig. 2, the

curved shadow line 74 indicates the wave form of the five impulses of current last described, in which the third and fifth impulses were curbed through the action of the controlling relays 46 and 86. The dotted curved 70 line 75 illustrates the wave form which would have resulted in the absence of curbing, as applied to the third and fifth impulses. The dotted guide line 76 represents a wandering-zero present with the asymmetrical current condition which would result from uncurbed alternations indicated by the wave line 75. It will be understood that the resistance units D employed to effect curbing may be inductive and should be preferably 75 of adjustable type to permit ready calibration of values to suitably meet the capacity and inductance characteristics of the cable with relation to the potential and frequency of the signaling currents, etc. 80

85 Since the type and circuit arrangement of each one of the relays in the group B are typical one of another, and as the same is true with respect to the relays comprising the group C, it will be obvious that unless 90 two incremented half-wave impulses, of either polarity, are separated by an incremented half wave of the opposite polarity, the second incremented half wave will be curbed or reduced in strength. It will also 95 be clear that when two incremented impulses of either polarity are separated by an incremented impulse of inverse polarity, the second incremented impulse corresponding with the first incremented impulse will not 100 be curbed. In establishing operations for an incremented half wave a relay in the group B will always close a circuit for the operation of a relay in the group C, and such C relay will be located in the third 105 position, in advance or to the right of the relay in the group B. To illustrate this point, on operating to increment an impulse, relays 2, 22, 42, 62 and 82 of the group B respectively close an operating circuit for 110 corresponding relays 46, 66, 86, 6 and 26 in the group C. In turn, the order in which the relays in group C are secondarily disabled by the relays in the group B is always one position to the right, that is, in the 115 group B, relays 2, 22, 42, 62 and 82 respectively disconnect relays 26, 46, 86 and 6 of the group C. 120

In connection with the relays of group C, it will be noted that the current sources 11, 31, 51 and 71, as interconnected through the relays 26, 46, 66 and 86, are in a closed loop circuit, and in order to prevent current action in this loop, it will be noted that the four current sources are connected to alternately oppose one another, thereby establishing a neutralizing or differential effect in this circuit. A fifth source of current 91 serves to operate the relay 6, and for convenience is connected in the circuit which 130

normally stands open at the contacts 65 of the relay 62.

Referring to Fig. 3 of the drawing, except for two windings on each one of the curbing relays C, this alternate arrangement is the same as the transmitter equipment shown in Fig. 1, and for convenience of description, similar characters of reference have been employed to indicate like parts 10 in this portion of the drawing. As indicated, each relay in the group C is marginally adjusted in such a manner that current must be present in both the right and left-hand winding, before the relay will operate. 15 In describing the features of this arrangement, let it be assumed that a combination of impulses prepared at the contacts A, establish operation of relays 2, 42, and 82, while relays 22 and 62 remain inert. Operation of the relay 2, in addition to closing a circuit from the bus conductor 35 to the segment 10, also establishes a circuit from a source of grounded current 95, through contacts 5 of the relay 2 and the left-hand 20 winding of the relay 46 to earth, and since the relay 22 is inert, its contacts 24 maintain the source 95 through the right-hand winding of the relay 46 to earth. Such energization of the two windings of the relay 46 is cumulative and operates this relay to close its contacts 48, thereby connecting the resistance unit 49 in series with a connection established through the contacts 43 of relay 42 between the bus-conductor 35 and the segment 50. The contacts 45 of the relay 42 connect the source 95 through the left-hand winding of the relay 86, and contacts 64 of the relay 62 maintain the source 95 through the right-hand winding of relay 30 40 45 50 55 60 65 70 75 80 85 90 95 100 105 110 115 120 125 130 95 to earth. Therefore, cumulative current action in the relay 86 causes it to operate and through its contacts 88 to establish the resistance unit 89 in series with a connection extending from the segment 90 through the contacts 83 of the relay 82 to the bus-conductor 35. Through the contacts 85 of the relay 82, the source 95 is connected over the left-hand winding of the relay 26, but due to the right-hand winding of this relay being disconnected at the contacts 4 of the relay 2, it continues inert.

It will be clear that the conditions now present on the equipment will result in the distributor brush 38 effecting changes of current in the line 13 corresponding with a sequence comprising a positive impulse of maximum strength, a negative impulse of minimum strength, a positive impulse of curbed or reduced strength, a negative impulse of maximum strength and a positive impulse of curbed strength. On arriving at the segments 55 and 56, the clearing out brush 39 causes the magnet 53 to operate and advance the tape, thereby releasing the relays 2, 42 and 82, which in turn respec-

tively permit the relays 46 and 86 to restore.

In the alternate arrangement, it will be noted that a single source of grounded current 95 is substituted for the five independent current sources 11, 31, 51, 71 and 91 employed in the first arrangement. Also that the normal contacts of each relay in the group B establish current from the source 95 through the right-hand winding of an associated relay in the group C, but since the latter relays are designed or adjusted for marginal operation only, they remain inert until a circuit is completed through both the right and left-hand windings as described. 70 75 80 85

Since the arrangement shown on Fig. 3 may be substituted for the arrangement shown in Fig. 1 and as its features of operation, other than those already described, are the same as those of the first arrangement, further description of the system will not be necessary. 3 85

In the matter of interconnections between various combinations of relays, it will be mentioned that in a multiplex system, in which an even number of sending segments are employed, the interconnection between the transmitting relays B and the modifying relays C may be completed by interconnecting the first relay of one group with the last relay of the other group. 90 95

Since telegraphic selection is effected through different amplitudes of half-wave alternating currents, which may form asymmetrical wave currents, impulse receiving devices do not ordinarily discriminate between the polarity of the impulses. Therefore, in the case of signal transmission in which a five-unit code is employed, the groups of impulses would alternately change 100 in the order of their polarity. In a four arm or quadruplex distributor having five impulse segments to a quadrant, the segments in each quadrant would be maintained in a fixed polarity relation to the currents developed by the alternating current generator, the first and second quadrants corresponding in polarities one with the other, while the third and fourth quadrants would correspond with each other but be of opposite 105 110 115 120 125 130 polarity combinations as compared with the quadrants 1 and 2. In a similar manner each sextant of a sextuplex distributor would continue responsive to a uniform order of polarities, the polarity relations reversing in successive sextants. Such relation would, of course, be present in a multiplex distributor of any capacity wherein an even number of arms or segment zones were present, and conversely the order of the polarities would reverse at each revolution of the trailer arm on distributors having an odd number of arms. It will be clear that in order to control impulse receiving devices adapted to discriminate between polarities 130

as well as different current amplitudes, constant potential conditions may be readily secured as described in connection with a distributor, without idly consuming or wasting any impulse or half-wave current time.

5 It will be understood that the present invention may be readily applied to render the service described in connection with land lines when desirable, as in connection with 10 long telegraph circuits, or on lines over which telephonic or message transmission by other methods of communication is carried on simultaneously therewith.

What is claimed is:

15 1. In a telegraph system, a line circuit, a transformer included therewith, a potential reducing means included with said transformer, a source of current waves included with said transformer and said potential 20 reducing means, means for selectively controlling the operative condition of said potential reducing means in phase with said current waves to effect signaling, and means for selectively curbing said current waves.

25 2. In a telegraph system, a line circuit, a source of alternating current included therewith, a resistance, a plurality of selectable contacts, a plurality of first relays controlled by said contacts, a distributor coöperating 30 with said relays to render said resistance effective to vary the amplitude of half-wave intervals of said alternating current to effect signaling, a plurality of resistances, a second plurality of relays controlled by said first 35 relays to control said plurality of resistances to further modify the amplitude of said half-waves in order to effect the zero current condition of said line.

3. In a telegraph system, a line circuit, a 40 source of symmetrical current waves included therewith, means for selectively rendering said waves asymmetrical to effect signaling, means for modifying said asymmetrical waves to affect the zero-current condition of 45 said cable, and electroresponsive means controlled by said means for establishing said asymmetrical effects to control the operativeness of said modifying means.

4. In a telegraph system, a line circuit, a 50 source of alternating current included therewith, potential modifying means in circuit with said source, a plurality of selectable contacts, a first plurality of relays controlled by said contacts, a distributor coöperating 55 with said relays to control the operativeness of said potential modifying means to

vary the amplitude of half-wave intervals of said current to effect signaling, other potential modifying means, a second plurality of relays controlled by said first plurality of relays to operatively control said other potential modifying means to further vary the amplitude of predetermined ones of said half-waves.

5. In a telegraph system, a line circuit, a 60 source of alternating current included therewith, a plurality of selectable contacts, a plurality of first relays controlled by said contacts, a plurality of second relays controlled in a predetermined order by said first 65 relays, a distributor, a resistance unit successively controlled by said first relays and said distributor to selectively vary the amplitude of half-wave intervals of said current to effect signaling, and a plurality of resistances controlled by said second relays to predeterminedly reduce the amplitude of 70 certain half-waves of increased amplitude.

6. In a telegraph system, a source of alternating current, means for transmitting impulses, means for varying the strength of current emitted from said source, and electromagnetic means responsive to current impulses for effecting the curbing of predetermined ones of the transmitted impulses. 80

7. A telegraph system comprising means for transmitting impulses, means for varying the strength of said impulses, a resistance normally ineffective, and means responsive to current impulses for rendering said 90 resistance effective to curb certain ones of the transmitted impulses.

8. In a telegraph system, a line circuit, a source of alternating current normally connected therewith, means for transmitting impulses, means adapted to vary the amplitude of half wave intervals of said current, and means rendered effective by local current impulses for thereby selectively curbing predetermined ones of the transmitted 95 impulses. 100

9. In a telegraph system, means for transmitting impulses, a plurality of relays operative for varying the strength of said impulses, and means operated by certain ones 105 of said relays for curbing predetermined ones of said impulses.

In witness whereof I hereunto subscribe my name this 5th day of October, A. D. 1917.

JOHN H. BELL.
